(57) **CLAIM**

The ornamental design for a headlight cover, as shown and described.

DESCRIPTION

FIG. 1 is a perspective view showing the front and left side of a headlight cover showing my new design residing on a vehicle which is shown in broken lines and forms no part of the claimed design.

FIG. 2 is a perspective view showing the front and left side of the headlight cover showing a first embodiment of my new design.

FIG. 3 is a perspective view showing the rear and left side of the headlight cover showing the first embodiment of my new design.

FIG. 4 is a front view showing the first embodiment of my new design.

FIG. 5 is a side view showing the first embodiment of my new design.

FIG. 6 is a rear view showing the first embodiment of my new design.

FIG. 7 is a top view showing the first embodiment of my new design.

FIG. 8 is a bottom view showing the first embodiment of my new design.

FIG. 9 is a perspective view showing the front and left side of the headlight cover showing a second embodiment of my new design.

FIG. 10 is a perspective view showing the rear and left side of the headlight cover showing the second embodiment of my new design.

FIG. 11 is a front view showing the second embodiment of my new design.

FIG. 12 is a side view showing the second embodiment of my new design.

FIG. 13 is a rear view showing the second embodiment of my new design.

FIG. 14 is a top view showing the second embodiment of my new design; and,

FIG. 15 is a bottom view showing the second embodiment of my new design.

1 Claim, 3 Drawing Sheets
